UNITED STATES PATENT OFFICE.

FREDERICK J. SCHLOER, OF TRENTON, NEW JERSEY.

DESIGN FOR AN INDICATOR-BOARD.

SPECIFICATION forming part of **Design No. 27,707**, dated **September 28, 1897**.

Application filed July 24, 1897. Serial No. 645,886. Term of patent 7 years.

To all whom it may concern:

Be it known that I, FREDERICK J. SCHLOER, a citizen of the United States, residing at Trenton, county of Mercer, State of New Jersey, have invented a certain new and original 5 Design for an Indicator-Board, of which the following is a specification.

The leading features of my design as shown in the drawing are, first, an indicator-board 10 A, of rectangular form, adapted to be suspended or supported in vertical position and having an exposed face, the central portion B of which is divided into a series of blocks somewhat similar to a checker-board, a top 15 margin or title-space C, and side margins D D', forming index-columns, and, second, a frame E, surrounding said board and forming ornamental top and bottom scrolls E' E' and

parallel side bars E² E², provided with adjustable indicator-fingers lapping over the 20 adjacent edges of the board or projecting beyond said bars, as shown. Upon the face of the board at the corners and bottom edge thereof appear ornamental attachments F, G, and H, completing the surface ornamentation 25 of the same.

What I claim is—

The design for an indicator-board substantially as shown.

In testimony whereof I affix my signature 30 in presence of two witnesses.

FREDERICK J. SCHLOER.
